UNITED STATES PATENT OFFICE.

MARCUS T. GOLDSMITH, OF NEW YORK, N. Y.

CHATELAINE-BAG HOOK.

SPECIFICATION forming part of Letters Patent No. 693,264, dated February 11, 1902.

Application filed December 5, 1901. Serial No. 84,728. (No model.)

To all whom it may concern:

Be it known that I, MARCUS T. GOLDSMITH, a subject of the Czar of Russia, and a resident of the city of New York, borough of Manhattan, in the county and State of New York, have invented a new and Improved Chatelaine-Bag Hook, of which the following is a full, clear, and exact description.

The object of the invention is to provide a new and improved chatelaine-bag hook which is simple and durable in construction and arranged to securely hold the hook in position on the waist-belt of the wearer against accidental detachment or removal by unauthorized persons, at the same time allowing the wearer to conveniently and readily attach or detach the hook whenever desired.

The invention consists of novel features and parts and combinations of the same, as will be fully described hereinafter and then pointed out in the claims.

A practical embodiment of the invention is represented in the accompanying drawings, forming a part of this specification, in which similar characters of reference indicate corresponding parts in all the views.

Figure 1 is a face view of the improvement as applied. Fig. 2 is a transverse section of the same, showing the hook locked against removal from a waist-belt. Fig. 3 is a like view of the same, showing the hook unlocked for removal from the waist-belt. Fig. 4 is a rear face view of the improvement. Fig. 5 is a sectional face view of the same, and Fig. 6 is a rear face view of a modified form of the improvement.

The improved chatelaine-bag hook consists of a hook proper, having an ornamental front shank A and a rear shank B, of which the latter is formed with an integral prong C, extending upwardly and forwardly to engage the inner face of a waist-belt D, on which the hook is applied so as to hold the hook against removal from the waist-belt. The prong C is preferably formed with two points at its free end, as plainly shown in Fig. 5, and the said prong is adapted to be inclosed at its free end by a slide E, mounted to slide up and down on a guideway F, formed on the rear shank B of the hook. The slide E is provided with an upwardly-extending handle E', lying close to the rear face of the rear shank

B, and on the upper end of the said handle E' is arranged a ring or similar device to allow the wearer to conveniently take hold of the ring to move the handle E', and with it the slide E, up and down on the guideway F.

When the slide E is in the lowermost position, the forwardly-projecting free end of the prong C is uncovered to allow the points thereof to engage the waist-belt D, as plainly shown in Fig. 2, to prevent removal of the hook from the waist-belt. When the slide E is, however, pulled upward by the wearer, the said slide moves over the free end of the prong C to inclose the same, and thereby prevent the points thereof from engaging the waist-belt D, or in case the prong-points are engaged with the belt a slight downward pressure of the hook and an upward pull on the slide will not only disengage the prong-points from the waist-belt, but will cause the slide E to inclose the free end of the prong C.

It is understood that the prong C is resili- 75 ent and normally projects out of the plane of the rear shank B and toward the front shank to engage the belt, and thereby to prevent removal of the hook from the belt, as above explained.

In order to properly guide the slide E and its handle E' on the guideway F, I provide the said slide with guide-lugs E³, and similar guide-lugs E⁴ are arranged on the handle. The guideway F is preferably formed by cutting out a portion of the shank B and leaving 85 the prong C extending in the guideway at its lower end, so that when the slide E is drawn upward it causes the prong to swing rearwardly into the space formed by the guideway, and when the slide E is moved downward the resiliency of the prong causes the same to swing inwardly into an active position. A stop B' in the form of a cross-bar may be arranged on the rear shank B across the guideway F for the upper end of the slide 95 E to abut against to limit the upward movement of the slide.

It is understood that the front shank A is provided at its lower end with the usual hook G for receiving the chain G' of a chatelaine-bag. As shown in Fig. 6, a spring H is employed to draw the slide E back to its normal lowermost position after the hook has been removed from the belt, the said spring H be-

ing preferably in the form of an elastic band engaging a cross-bar E⁵ on the handle E' and a cross-bar B² on the rear shank B.

Having thus described my invention, I claim as new and desire to secure by Letters Patent—

1. A chatelaine-bag hook, provided with a hook proper, the rear shank of which is formed with a resilient prong normally extending from the face of the rear shank in a forward and upward direction, and a slide movable lengthwise on the rear shank and arranged for inclosing the said prong, as set forth.

2. A chatelaine-bag hook, provided with a hook proper, the rear shank of which is provided with a guideway extending lengthwise of the shank, a prong integral with the rear shank and projecting from the face thereof in an upward and forward direction, and a slide movable on the said guideway and under the control of the wearer, the slide being arranged to inclose the said prong, as set forth.

3. A chatelaine-bag hook, provided with a hook proper, the rear shank of which is provided with a guideway extending lengthwise of the shank, a prong integral with the rear shank and projecting from the face thereof in an upward and forward direction, a slide mov-

able on the said guideway, and a handle on the slide and projecting upward to the top of the hook, the said handle being under the control of the wearer to move the slide up and down for inclosing the free end of the prong or to disengage the said free end, as set forth.

4. A chatelaine-bag hook, provided with a hook proper, the rear shank of which is provided with a guideway extending lengthwise of the shank, a prong integral with the rear shank and projecting from the face thereof in an upward and forward direction, a slide movable on the said guideway, a handle on the slide and projecting upward to the top of the hook, the said handle being under the control of the wearer to move the slide up and down for inclosing the free end of the prong or to disengage the said free end, and means for limiting the sliding movement of the said slide on the guideway, as set forth.

In testimony whereof I have signed my name to this specification in the presence of two subscribing witnesses.

MARCUS T. GOLDSMITH.
